UNITED STATES PATENT OFFICE.

GEORGE B. MERSHON, OF PHILADELPHIA, PENNSYLVANIA.

GRATE.

SPECIFICATION forming part of Letters Patent No. 281,384, dated July 17, 1883.

Application filed April 27, 1883. (No model.)

To all whom it may concern:

Be it known that I, GEORGE B. MERSHON, a citizen of the United States, and a resident of Philadelphia, in the county of Philadelphia and State of Pennsylvania, have invented certain new and useful Improvements in Grates, of which the following is a specification.

My invention relates to that class of grates in which the bars are provided with side lugs or fingers, and are rocked in order to clean the fire; and it consists of certain improvements in the construction of the bars, bar supports, and operating appliances, fully described hereinafter, and illustrated in the accompanying drawings, in which—

Figure 1 is a perspective view of the outside of a furnace, showing the bar-operating appliances. Fig. 2 is a plan of part of Fig. 1. Fig. 3 is a detached section of part of the rocking appliance. Fig. 4 is a sectional elevation, showing a grate-bar, part of the frame, and operating appliances. Fig. 5 is a plan of Fig. 4, and Fig. 6 a modification.

In that class of rocking-bar grates illustrated in various patents heretofore granted to me the bars have journals extending forward, and provided with arms connected with a cross-bar, by reciprocating which all the grate-bars will be simultaneously rocked. While this is serviceable for stoves and small furnaces, the simultaneous moving of all the bars is sometimes objectionable when the fire-bed is very large, owing to the difficulty of moving so great a number of bars, and because one portion of the fire will sometimes require raking when another portion will not. I overcome this objection by dividing the grate-bars into two or more sections and connecting the arms of each section to one connecting-bar, whereby each section or series of bars may be rocked independently of the others. Thus in Fig. 1 the connecting-bar B, attached to the arms of three of the grate-bars, may be operated independently of the bar B', connected to three others of the grate-bars.

Heretofore the arms D have been temporarily fastened by pins or otherwise to the projecting ends of the bar-journals. This has rendered their detachment and connection somewhat difficult. I therefore form in the ends of each journal a socket, x, adapted to receive the end of the arm D, which projects upward,

as shown at the right in Fig. 1, and is connected by a pin to the bar B, so that by simply lifting the latter all the arms D may at 55 once be detached.

Heretofore it has been common to so connect one of the bars of a grate as to permit it to be lowered, so as to discharge the contents of the fire-pot, it being difficult to lower two continuous bars, owing to the necessity of a swiveling connection at the rear and the space required by the latter. To enable me to lower any one or all of the bars, I dispense with the swiveling connection, and cast or otherwise 60 form at the under side of the bed-plate E, at the rear, a loop or series of loops, F, and I provide each bar G with a rear trunnion, a, which is horizontal adjacent to the bar, and is then curved downward, as shown in Fig. 4. The 70 horizontal portion of the trunnion lies in contact with the loop F, so that the bar will rock as usual; but when the front support is removed, it will fall, turning upon its bearing F, but without becoming detached therefrom. 75

The front support is a short shaft, H, supported in a hanger, I, so as to rock therein, and provided with a pin, b, which may limit the rocking motion, and with a rectangular stud, d, fitting a socket, e, in the end of the 80 bar. When the latter is to be a dropping-bar, the hanger I is slotted, so as to permit the shaft H to have a longitudinal movement to withdraw the stud from the socket e.

In a separate application for Letters Patent 85 a claim was allowed me for curving the sides of the teeth. In the drawings I have shown an equivalent construction, each tooth having a double bevel at the sides, so that when the tooth of one bar strikes that of another they 90 will slip past each other without interlocking.

To prevent the burning away of the bar, and especially of the teeth, I construct the same with transverse slots or recesses y, crossing the bottom of the bar and extending nearly to the 95 ends of the teeth. This insures a plentiful supply of air, and leaves bridges i at the sides of each slot, between the same and the usual longitudinal slot, w, which maintain the strength and rigidity of the bar. These long 100 transverse slots insure a beneficial supply of air, where simple perforations in the teeth would be useless.

In large grates, where the bars are long and

heavy, the labor of rocking them is frequently very great, even when the usual lever, constituting practically an extension of one of the arms D, is employed. I obviate this by using a bell-crank lever, J, having its fulcrum at its corner angle, u, and connected at the short arm to the bar B. By this means I am enabled to rock the bars and employ as great a leverage as may be necessary to readily effect this object.

While a pin entering an opening in the lever J may serve as a fulcrum, I prefer to use a disk, K, fitting a circular recess in a bracket, L, having a pin, f, extending through a hole in said bracket, and a fin, t, with a socket, v, to receive a short arm, s, of the lever. By this arrangement the pin f serves merely to hold the disk in place, while the strain all comes upon the periphery of the disk at its contact with the edge of the socket in the bracket. A similar pivoted socket-piece, K', may be connected to the end of the bar B; or any other suitable connection may be employed.

As the bracket L and operating-lever would occupy an amount of space in a furnace-room which is not always perfectly available, I hinge the bracket L, at its inner end, q, to a plate secured to the wall or case of the furnace, so that the parts may be brought to the position shown in Fig. 1, and there held by a brace, p, during operation. The brace may then be detached or disconnected, and the bracket turned back against the wall, as shown in Fig. 2, so as to be out of the way. The bar B may also be in two sections, jointed at m, and a bolt, n, or other device will serve to hold the sections in place until the bracket is to be turned against the wall.

In many cases it is objectionable to put the arms D outside of the furnace. In such case I arrange the grate-bar transversely, as shown in Fig. 6, with the arms D extending around at one side of the furnace, and the connecting-bar B extending through a hole, g, in the front wall. The arm may in such case be jointed, and a hinged bracket, L, may be hung to the front wall to operate in connection with a detachable lever, as before described.

I do not abandon or dedicate to the public any patentable features set forth herein and not hereinafter claimed, but reserve the right to claim the same either in a reissue of any patent that may be granted upon this application or in other applications for Letters Patent that I may make.

I therefore claim—

1. The combination, with the bars having sockets x, of a series of separate detachable arms, D, each fitting one of said sockets, and all connected to a bar, B, substantially as set forth.

2. The combination, in a grate, of stationary loops F, attached to the frame, and rocking bars G, provided with rear journals bent at the ends, substantially as set forth, and with movable supports at the front ends.

3. A rocking grate-bar provided with lateral teeth, and with slots or air-channels y, extending transversely through the bar and into the teeth at the opposite sides, substantially as specified.

4. The combination, with a furnace having rocking bars connected to an operating-bar, B, of a crank-lever, J, pivoted to a movable bracket at the side of the furnace and connected to the bar B, substantially as specified.

5. The combination, with a furnace having rock-bars and an operating-lever, J, of a bracket supporting said lever and hinged to the body or casing of the furnace, substantially as set forth.

6. The combination of the hinged bracket, operating-lever supported thereby, and rock-bars connected to a bar, B, jointed as set forth.

7. The within-described swiveling bearing 85 for the operating-lever, consisting of a disk fitting a socket in the bearing-piece, provided with a connecting-bolt, f, and having a socket, v, substantially as set forth.

In testimony whereof I have signed my name 90 to this specification in the presence of two subscribing witnesses.

GEORGE B. MERSHON.
